UNITED STATES PATENT OFFICE.

VICTOR DALLEMAGNE, OF PARIS, FRANCE.

SPARK-EXTINGUISHING APPARATUS.

Application filed August 28, 1923. Serial No. 659,792.

To all whom it may concern:

Be it known that I, VICTOR DALLEMAGNE, citizen of the French Republic, residing at Paris, Department of Seine, France, have 5 invented certain new and useful Improvements in Spark-Extinguishing Apparatus, of which the following is a specification.

The present invention relates to a device applicable in particular to locomotive smoke boxes, and more generally to all chimneys, either industrial or otherwise, with a view to stop the sparks, regulate the draught, spare the fuel, and stop the soot, which device may be, if desired, located in a recess 15 provided for the purpose.

Two embodiments of the invention are illustrated, by way of example, on the annexed drawing, in which:

Figure 1 shows an arrangement for locomotives, comprising a serpentine metal sheet combined with a conical steam baffle cone;

Fig. 2 is a view of an arrangement slightly modified as to certain details from that illustrated in Fig. 1, such modified arrangement being represented as taken to pieces;

Fig. 3 is a view similar to Fig. 1, but showing a further modified form of spiral baffle;

Fig. 4 is a view generally similar to Fig. 2, but showing the modified form of spiral baffle represented in Fig. 3.

The device shown in Figure 1 is essentially characterized by the combination of a 35 spiral or serpentine metal sheet 1, fast or movable, located in a drum 5 which encircles the exhaust pipe 2 and a baffle 3 which may take any shape, that of a cone, for instance.

Said baffle, against which the sparks 40 strike and go out as they escape from the fire, is located on an appropriate support linked to cylinder 4, itself located in the flue 4' of the locomotive, said cylinder being closed in its lower part by a truncated 45 core 9 which carries drum 5.

The object of baffle 3 located above the serpentine metal sheet, is to reduce the section of the steam passage and to direct the steam with a certain force against the walls 50 of the flue, so as to increase the draught, especially when the flues are of a small height. The sparks issuing from the fire strike the serpentine metal sheet 1 and are extinguished.

The regulation of the draught is obtained 55 by widening or narrowing, according to re-

quirement, the spirals of serpentine metal sheet 1 by means of an appropriate device, consisting of two tightening parts 15, for instance.

In the form of execution shown in Figure 2, on the ends of serpentine metal sheet 1 are slidably mounted two adjustable parts 10' and 11 enabling the serpentine metal sheet to vary in length, thus regulating the draught.

Said form of execution is further characterized in that with a view to make the serpentine metal sheet easily accessible when it is required to remove it for cleaning or repairing the tube system of the engine, the drum 5 is composed of three elements a, b, c, which may be assembled by any appropriate means, such as hooks 6 engageable with keepers 7.

The upper edge of drum 5 is provided with an inturned rim or flange 8 having secured to it depending pins carrying rollers 9' which are designed to travel along an annular track or recess 10 formed on the lower edge of the cone 9.

This latter arrangement is meant to keep up and guide elements a, b, c during their mounting and demounting.

In the form shown in Figure 3, the serpentine metal sheet 1 is replaced by a baffle 1', here represented as of frusto-conical shape with its apex directed upward, said baffle being provided with a space or gap 9'', the extent of which is controlled at will 60 by means of the sliding parts 10' and 11.

Above the gap or open space 9'' mentioned before, is placed a second baffle 12 having, like the first one, sliding parts 13 to enable its surface to be varied at will. Said 65 sliding parts may be controlled simultaneously with those of cone 1'.

Of course, the forms of execution hereinbefore described are given merely by way of example and the constructive dispositions 70 may be modified without departing from the scope of the invention.

Having now particularly described and ascertained the nature of my said invention as well as the manner in which the same is to 75 be performed, what I claim as new is:

1. A spark extinguisher, comprising a baffle adapted to be mounted on the exhaust pipe of a locomotive, a frusto-conical member located above the baffle and adapted to 80 be attached to the stack of the locomotive, said member having an annular circumfer- 85

2
ential track at its lower end; and an open-ended drum located below the frusto-conical member and enclosing the baffle, said drum having a continuous lateral flange or rim at its upper end provided with roller-carrying members engaged with said track to suspend the drum therefrom.

2. A spark extinguisher, comprising a baffle adapted to be mounted on the exhaust pipe of a locomotive, a frusto-conical member located above the baffle and adapted to be attached to the stack of the locomotive, said member having an annular circumferential track at its lower end, and an open-ended drum enclosing the baffle and having a continuous lateral flange or rim at its upper end provided with roller-carrying members engaged with said track to suspend the drum therefrom; said drum consisting of a plurality of similar sections having coacting fastening devices at their adjacent edges to removably connect them together.

3. In a spark extinguisher, the combination of a baffle adapted to be mounted on the

exhaust pipe of a locomotive; a pair of sliding plates adjustably mounted on the baffle to vary its effective length; an open-ended drum enclosing the baffle; and supporting means for the drum.

4. In a spark extinguisher, the combination of a baffle adapted to be mounted on the exhaust pipe of a locomotive; a pair of sliding plates adjustably mounted on the baffle to vary its effective length; a frusto-conical member adapted to be attached to the stack of the locomotive above the baffle; an open-ended drum suspended from the lower end of the frusto-conical member and enclosing the baffle; and a baffle with the stack above and in line with the exhaust pipe and the first baffle.

5. A spark extinguisher, comprising a spiral metal sheet adapted to be mounted on the exhaust pipe of a locomotive, and a pair of sliding plates adjustably mounted on the ends of said sheet to vary its effective length.

In testimony whereof I affix my signature.

VICTOR DALLEMAGNE.
